UNITED STATES PATENT OFFICE.

CHARLES H. ORTS, OF SILVER CREEK, NEW YORK.

CRUPPER-COUPING.

SPECIFICATION forming part of Letters Patent No. 295,192, dated March 18, 1884.

Application filed January 12, 1884. (No model.)

To all whom it may concern:

Be it known that I, CHARLES H. ORTS, a citizen of the United States, residing in Silver Creek, in the county of Chautauqua and State 5 of New York, have invented certain new and useful Improvements in Crupper-Couplings, of which the following is a specification.

The object of my invention is to provide a convenient means for readily attaching or detaching the crupper or tail strap of a harness, all of which will be fully and clearly herein-after shown by reference to the accompanying drawings, in which—

Figure 1 is a front or face view. Fig. 2 is 15 a back view, showing a separate view of the detachable portion of the device; and Fig. 3 is an enlarged longitudinal central section through the device.

The body of the coupling, *a*, is of a flat tubular form, provided with a plate, *a'*, jointed to the body by a joint, *a''*, made in any well-known way. (See Figs. 1 and 3.) It is provided with a spiral spring, *a''*, made in the usual way, to keep the hook - catch *a''* down 25 in place; but a flat or other well-known spring may be used in its place for accomplishing the same result.

c represents the connecting device. It is provided with a tongue, *c'*, which enters the 30 tube, and it has a hole, *c''*, through which the hook or catch *a''* passes when the coupling

is secured together. The outer end of the part *c* is made of thin sheet metal, and is placed to one side, as shown in Fig. 3, so as to receive the strap. It is provided with holes *c''*, through 35 which rivets *c'* are passed to secure the strap thereto. The opposite end of the body is also provided with a similar part, *c'*, of sheet metal, having the holes *d* for riveting the strap thereto. It will be seen by this arrangement 40 that the crupper - strap may be easily and quickly disconnected by pressing with the thumb or finger on the part *e* of the jointed plate *a'*, and thereby raise the hook *a''* out of the hole *c''* in the tongue *c'*, so as to release it. 45 It is connected by simply pushing the tongue in, which operation raises the spring-catch until the hole comes under its point, when it springs into place and holds it securely.

I claim as my invention—

A crupper-coupling consisting of the flat tubular body *a*, having the flat strap-connecting portion *c'*, and a plate and catch jointed thereto, and provided with a spring, *a''*, in combination with the connecting-piece *c*, having the flat strap-connecting portion *c''*, and a tongue, *c'*, having a hole, *c''*, substantially as and for the purposes described.

CHAS. H. ORTS.
